UNITED STATES PATENT OFFICE.

SILAS M. FORD, OF ST. PAUL, MINNESOTA.

LATH-BOARD.

1,188,536.

Specification of Letters Patent. Patented June 27, 1916.

Application filed January 10, 1916. Serial No. 71,311.

To all whom it may concern:

Be it known that I, SILAS M. FORD, a citizen of the United States, residing at St. Paul, in the county of Ramsey and State of Minnesota, have invented certain new and useful Improvements in Lath-Boards, of which the following is a specification.

My invention relates to improvements in lath-board of waterproofed paper or other flexible sheeting designed to be fastened to the studding or beams of buildings to serve as a foundation for plaster, and corrugated to form lath like projections and intermediate depressions or valleys, the valleys on one side forming air spaces and the valleys on the other side forming plaster receiving spaces.

The lath board is most conveniently made in large sheets which can be rolled or packed for shipping and afterward cut to the size and shape desired in use.

It is the object of the invention to provide improved means for binding the corrugations together and holding them to form, so that they will not spread apart or become crushed or flattened in use or handling, with the consequent impairment of their capacity as air containing or plaster receiving spaces.

With this object in view I have provided transverse binding strips secured at intervals across the face of the board and having pressure resisting instrumentalities extending inwardly into the valleys, and preferably through the board itself, in position to abut against one or both of the sides of the projections and so resist the lateral thrust of the same when they are under compressive or lateral pressure.

More particularly the invention consists in the construction, combination, and arrangement of parts hereinafter described and claimed.

In the accompanying drawings forming part of this specification, Figure 1 is a perspective view of a fragment of lath board embodying a binding strip formed with abutment prongs which pierce the board; Fig. 2 is an end view of the same; Fig. 3 is an end view of the same provided with a backing sheet through which the prongs are passed; Fig. 4 is a perspective view of the preferred form of binding strip; Fig. 5 is a perspective view of a modified form of binding strip; Fig. 6 is a perspective view of a fragment of lath

board wherein the abutment prongs support one side only of each lath projection; Fig. 7 is a perspective view of a fragment of lath board wherein the abutment instrumentalities do not extend into the lath board itself; Fig. 8 is a view, partly in end elevation, and partly in section, of a fragment of board wherein the abutment instrumentalities consist of pins or nails extending through the strips; and Fig. 9 is a similar view where the abutment instrumentalities consist of staples.

The lath board to which this invention relates is made of flexible sheeting, preferably waterproofed paper, pressed or molded to form corrugations or alternate projections and depressions or valleys, so that the depressions on one side will form the valleys on the other side and vice versa. I prefer to form the corrugations in plaits, as it were, of keyed lath shape, as shown in the drawings, where 2 represents the lath projections on one side of the board and 3 the lath projections on the other side. Between the lath projections 2 are intermediate valleys or depressions 4 formed by stamping up the lath projections 3 on the other side of the board, and there are similar depressions or valleys 5 between the lath projections 3, these valleys 5 being formed by stamping up the projections 2. The valleys or longitudinal channels 4 which are open on the plastering face of the board serve as plaster receiving spaces, while the oppositely facing valleys or channels 5 under the hollow stamped up lath projections 2 serve as dead air heat insulating and sound deadening spaces.

To hold the lath projections to form so that they will not spread apart or become crushed or flattened in use, as well as to provide keys for the plaster, I have provided sheet metal binding strips 6 which extend transversely across the face of the corrugations at suitable intervals apart and carry lateral abutment or pressure resisting instrumentalities which extend into the valleys and may themselves pierce the board and thus serve to secure the strips thereon.

In the form shown in Figs. 1 to 4 of the drawings the strips are provided with stamped up prongs 7 adapted to enter the valleys 4 and pass through the face of the lath projections 3. After piercing the lath projections the ends of the prongs may be

upset and clenched as shown in Figs. 1, 2, and 3. In Fig. 3 of the drawings the board is shown provided with a backing sheet 8 through which the prongs are passed and clenched, but the backing sheet may, if desired, be secured to the corrugated board by asphalt or other suitable binder independently of the prongs 7. The prongs are arranged in pairs and are spaced apart to correspond with the valleys of the board so that the prongs of each pair will bear against the opposite side edges of the two adjacent projections. Thus when the board is subjected to pressure the side edges of the lath projections will be opposed and held by the prongs so that the projections will be prevented from spreading and being crushed in.

In Fig. 6 of the drawings is shown a modified form wherein the binding strip is provided with only one prong for each valley or depression 3, so that only one side of each lath projection 2 will be supported by a prong.

In Fig. 7 is shown another modification wherein the board is provided with a backing sheet 8, and the prongs 9 of the strip 6 are not long enough to pierce the corrugated board, but merely enter the valleys, like the prongs 7, in position to abut against the side edges of the lath projections. In this case it is necessary to secure the strips to the corrugated board by independent fastening means, such as the pins 10 or staples 11, which may also pass through the backing sheet and form a means of securing the corrugated board to the backing sheet.

In Figs. 8 and 9 are shown modifications wherein the abutment prongs, instead of being stamped up from the strips 6, consist of independent pins 12 or staples 13 passing through the strips and driven through the corrugated board, and also, if desired, the backing sheet with their ends clenched or upset.

The pins 12 and staples 13 extend into the valleys in position to abut against the opposite side edges of the adjacent projections similarly to the prongs shown in Figs. 2 and 3, but it will be understood that, if desired, they can be so arranged as to abut against one edge only of these projections similarly to the prongs shown in Fig. 6. Thus the transverse strips above described with their prongs extending into the valleys of the corrugations and confining the opposite sides of the keyed lath corrugations serve effectually to keep the corrugations to form by opposing the lateral thrust of the corrugations when the same are subjected to crushing pressure, and also serve to bind the corrugations together. And when the prongs pass through the corrugated sheet or backing board they also serve most efficaciously to prevent this spreading of the

projections as well as directed to resist the crushing pressure and to secure the projections firmly to the backing sheet.

By the term "abutting" as applied to the prongs is meant that the prongs are either normally in contact with the sides of the projections or close enough to them to oppose their lateral thrust when they are subjected to spreading force or crushing pressure.

I claim:

1. A lathboard comprising a sheet of flexible material corrugated to form lath projections and intermediate valleys, and binding strips extending transversely across the face of the projections and having prongs extending into the valleys and forming lateral supports for the projections.

2. A lathboard comprising a sheet of flexible material corrugated to form interspaced lath projections and intermediate valleys, binding strips extending transversely across the face of the projections, prongs depending from the binding strips and projecting down into the valleys in position to form lateral supports for the projections and extending through the board at the bottom of the valleys.

3. A lathboard comprising a sheet of flexible material corrugated to form interspaced projections and intermediate depressions, binding strips extending transversely across the face of the projections, and prongs carried by the binding strips at intervals corresponding to the distances between the sides of adjacent projections and extending into the depressions so as to abut against both sides of said projections, whereby to form lateral supports on each side thereof.

4. A lathboard comprising a sheet of flexible material corrugated to form interspaced projections and intermediate valleys, binding strips extending transversely across the face of the projections, and prongs carried by the binding strips and extending into the valleys so as to abut against both sides of said projections, whereby to form lateral supports on each side thereof and extending through the board at the bottom of the valleys.

5. A lathboard comprising a sheet of flexible material corrugated to form interspaced projections of keyed lath shape and intermediate valleys, binding strips extending transversely across the face of the projections, and prongs carried by the binding strips and projecting into the valleys in position to abut against both side edges of said keyed lath projections, whereby to form lateral supports on each side thereof.

6. A lathboard comprising a sheet of flexible material corrugated to form keyed lath shape projections and intermediate valleys, binding strips extending transversely across the face of the projections, and prongs de-

pending from said strips and projecting into the valleys in position to form lateral supports for the projections.

7. A lathboard comprising a sheet of flexible material corrugated to form interspaced projections and intermediate depressions, sheet metal binding strips extending transversely across the face of the projections and having prongs struck up at intervals,

said prongs extending into the valleys and 10 forming lateral supports for the sides of the projections.

In testimony whereof I affix my signature in presence of two witnesses.

SILAS M. FORD.
